LAST THIMBLE

William J. Ripley, Marlboro, Mass., assignor to
 Koehler Manufacturing Company, Marlboro,
 Mass., a corporation of Massachusetts

Application March 3, 1950, Serial No. 147,539

1 Claim. (Cl. 16—2)

1

This invention relates to an improved last thimble such as is customarily used in the cone of a last to receive the last spindle, and more particularly the invention is concerned with spinning a last thimble from a tubular body.

Last thimbles are now manufactured from flat sheet metal by the punch press process where they are drawn to shape and size by relatively expensive and time consuming annealing operations; also from solid bar metal by the screw machine process wherein the stock is drilled to shape and size, requiring excess amounts of stock and labor. Attempts have also been made to form a thimble by spinning one end of a tubular body closed, but in all of these attempts it has been found necessary to employ some kind of heat which greatly detracts from the value of such operations and has discouraged their use.

The present invention deals with the problem indicated and seeks to devise a method of spinning tubular bodies to form a closed end thimble which is characterized by a suitably heavy and wear-resistant end wall and shoulder construction and which can be manufactured more cheaply and quickly than presently manufactured last thimbles. It is also an object of the invention to provide a method of spinning in which the use of heat is avoided and breaking of edges of the tubular stock is prevented.

These and other objects and novel features will be more fully understood and appreciated from the following description of a preferred embodiment of the invention selected for purposes of illustration and shown in the accompanying drawings, in which:

Fig. 1 is an end elevational view of a tubular member employed in making the last thimble of the invention;

Fig. 2 is a side elevational view of a length of the tubing illustrated in Fig. 1;

Fig. 3 is an assembly view indicating the tubular member of Fig. 2 supported in a chuck with a spinning tool arranged in juxtaposition thereto;

Fig. 4 is another elevational view of the tubular stock and spinning tool assembly and further indicating the spinning process in a partly completed state;

Fig. 5 is a cross-sectional view further illustrating the tubular stock at the point in its preparation resulting from use of the spinning tool shown in Fig. 4;

Fig. 6 illustrates another spinning tool in engagement with the tubular member illustrative of the step of finally closing one end of the latter member; and

2

Fig. 7 is a longitudinal cross-sectional view showing the completely spun closed-in construction.

According to the invention I provide for an attenuated spinning movement in which working or drawing of the metal takes place along a reversely curved path of contact made possible by a novel spinning tool shape.

In the structure shown in the drawings, numerical 10 denotes a tubular body preferably composed of a substance such as steel of suitable hardness, and chosen of a length designed to provide a conventional shoe last thimble. The tubular member 10 in accordance with the invention is supported in a rotating work-holding member or chuck 12, as shown in Fig. 3, in position to be engaged by a spinning tool, such as that shown at 14, also mounted for rotation and indicated in Fig. 3. The spinning tool is formed with a reversely curved shoulder 16 which terminates in a reduced end portion 18. The curve which defines the shoulder portion and reduced end is so chosen that its radius extends only part way of the radius of the tubular stock 10.

In accordance with the invention, a reversely curved spinning tool of the character described and preferably of a diameter much longer than that of tubular section 10, is brought into engagement with the latter element in such relative position that the edges 20 of the left-hand edge of the tubular member 10, as viewed in Fig. 3, project beyond the shoulder portion 16 of the tool and the latter portion bears against intermediate portions of the tube periphery. As the spinning operation progresses the shape of the

reversely curved shoulder 16 is duplicated on intermediate portions of the tubular member 10 and simultaneously edge portions 20 of the tubular member are brought into converging relation without actually having any direct contact

of the spinning tool thereagainst, and there thus results a spinning operation in which a rolling-over of the edge of the tubular stock takes place with an inner tip 22 gradually being formed centrally of the longitudinal axis of the tube, as is more clearly shown in Figs. 4 and 5. A series of tools of progressively smaller sizes may be utilized in developing the tip formation.

It will be seen that the edges 20 throughout this part of the spinning operation receive little direct contact such as would tend to break or crack these edges apart, as is the case in conventional types of spinning operations. Also, this reversely curved spinning tool construction permits a forming and drawing of the tubular stock to take place gradually along a considerable area

of the tube periphery without the aid of heating, such as is normally resorted to in spinning with conventional type spinning tools.

When the metal is drawn to form the tip 22 in a greatly reduced form, a final spinning operation may be carried out employing a spinning tool 24, such as that illustrated in Fig. 6. This tool is provided with a flat end face 25 which can, at this time, be brought to bear against the reduced tubular portion 22 to contact and flatten the portion into a solid end wall 28, as shown in Fig. 7.

I have found that in thus cold spinning the tubular body I may effect a very desired hardening of the metal throughout the region which extends from the closed bottom wall upwardly along the shouldered portions and then well beyond the shoulders into the intermediate portions of the peripheral wall of the tube. This extended region of hardening I find to be important, both in the respect that the work hardness of the metal is materially increased by the cold spinning at the bottom section of the thimble and the shoulders, and also in the respect that substantially increased work hardness is provided for the peripheral wall portions just above the shoulders. As a result, I am enabled to produce a thimble of an exceptionally heavy durable end wall and shoulder construction and, in addition, I impart a pronounced reinforcing at the region of the wall periphery lying immediately adjacent to the shoulders. The effect of this reinforcing is found to materially increase the life of the thimble and to greatly increase its resistance to shock and wear. As an instance of the relative change of hardening from the cold spinning, there may be cited in one tubular body, before spinning, a Rockwell hardness of B45 to 48, and after spinning there was produced a Rockwell hardness at the shoulders of the tubular body of from B69 to 70 and at the

center of the bottom of the spun tube a Rockwell hardness of from B60 to 62.

I have further found that by practicing a method of cold spinning along a reversely curved path of contact, I may provide for substantial savings in labor and material, with the result that a less expensive last thimble may be produced. No breaking of the edges is caused to take place and no undesirable heating effects occur. It will thus be seen that I have provided a desirable, efficient, and economical method of forming last thimbles, and have imparted desirable and novel characteristics to the thimble body produced by this method.

15 Having thus described my invention, what I desire to claim as new is:

20 A shoe last thimble comprising a tubular body having a closed end wall and a circumferentially shouldered portion extending upwardly therefrom and merging with said body, said end wall, shouldered portion, and peripheral body portions immediately adjacent the circumferentially shouldered portion being shaped by cold spinning to provide a work hardness of said parts 25 appreciably greater than that of remaining portions of the thimble.

WILLIAM J. RIPLEY.
